UNITED STATES PATENT OFFICE.

CALVIN MARTIN AND MIKE BEASLEY, OF DICKSON, TENNESSEE.

AUTOMATIC RETAINING-VALVE.

No. 879,783.

Specification of Letters Patent. Patented Feb. 18, 1908.

Application filed August 10, 1906. Serial No. 330,003.

To all whom it may concern:

Be it known that we, CALVIN MARTIN and MIKE BEASLEY, both citizens of the United States, and residents of Dickson, in the county of Dickson and State of Tennessee, have invented a new and Improved Automatic Retaining-Valve, of which the following is a full, clear, and exact description.

The invention relates to fluid pressure brakes of the Westinghouse and like types, and its object is to provide a new and improved automatic retaining valve, arranged to retain the pressure in the brake cylinder while recharging the auxiliary reservoir, thus preventing the acceleration of the train, especially when running down a steep grade.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a side elevation of the improvement as applied; Fig. 2 is a cross section of the improvement on the line 2—2 of Fig. 3; Fig. 3 is a longitudinal central section on the line 3—3 of Fig. 2, and Figs. 4, 5 and 6 are like views of the same, and showing the parts in a different position.

The casing A of the automatic retaining valve is connected by a pipe B with a branch pipe C' of the train pipe C, and which branch pipe C' is connected with the triple valve D of the usual construction. A pipe E connects the casing A with the triple valve exhaust, to allow the air to escape from the brake cylinder F on the release of the brakes by way of the retaining valve, as hereinafter more fully described, and the pipe G connects the auxiliary reservoir H with the automatic retaining valve. The train pipe C is connected with the usual engineer's valve I connected with the main reservoir J, as plainly indicated in Fig. 1.

The casing A is provided with a cylinder A', into the outer or left hand end of which opens the pipe B, and in the said cylinder A' reciprocates a piston K. The other end of the cylinder A' opens into a valve chamber A² provided in its bottom with a valve seat A³

for a slide valve L to travel on, and which slide valve has its under side provided with a cavity L' for connecting the pipe E with the exhaust port E' formed in the casing A and leading to the atmosphere. A spring L² presses the slide valve L to hold it to its seat A³. Into the valve chamber A² opens the pipe G so that the pressure of the auxiliary reservoir H is exerted against the outer or right hand face of the said piston K, and when the pressures on the opposite faces of the piston K are equal then the piston K is in its normal midway position.

The piston K is provided with a stem K' extending through the valve chamber A² and provided with spaced collars K² and K³ adapted to engage the opposite ends of the slide valve L, to shift the latter on its seat A³, as hereinafter more fully described. The valve stem K' also extends into a spring chamber A⁴ formed on the casing A and containing a spring N coiled on the said valve stem K' and abutting with its outer end on the screw plug O screwing in the outer end of the chamber A⁴, for regulating the tension of the spring N, the inner end of which rests against a washer P normally seated on a seat A⁵ formed on the inner end of the chamber A⁴, between the latter and the chamber A². This washer P is adapted to be engaged by the collar K³, to place the spring N under tension when releasing the brakes, as hereinafter more fully described and illustrated in Fig. 6. A cap A⁶ closes the outer end of the casing A. The spring N is preferably set to resist about ten pounds while recharging after the brakes have been set.

The operation is as follows: When the brakes are released the several parts of the automatic retaining valve are in the position illustrated in Fig. 3, that is, the piston K is in a midway position in the cylinder A' and the slide valve L connects the triple valve exhaust pipe E with the atmosphere by way of the cavity L' and the port E'. The collar K³ is now in engagement with the right hand end of the slide valve L, but the tension device, consisting of the spring N and washer P is inactive as the washer P rests on the seat or shoulder A⁵. Now, presuming that the fluid pressure brake is charged up to standard or 70 pound train pipe pressure and the main reservoir J is charged to 100

pounds, then the piston K is subjected to 70 pounds pressure on both faces. Now, when the engineer reduces the pressure in the train pipe C with a view to set the brakes 5 then the pressure against the left hand face of the piston K is correspondingly reduced, and the preponderance of pressure against the right hand face of the piston now shifts the latter from the right to the left to the 10 position shown in Fig. 4. The piston K in moving into this position shifts the slide valve L as the collar K³ carries the slide valve along until the latter is moved into a closed position, that is, the pipe E and the 15 exhaust port E' are disconnected. The brakes are now applied and if the engineer wishes to recharge the train pipe C and the auxiliary reservoir H he places the valve I into running position, thus allowing the air 20 to pass from the main reservoir J through the feed valve of the engineer's valve I into the train pipe C. Now when this takes place a preponderance of pressure passes into the cylinder A' at the left hand side 25 thereof, so that the piston K is shifted back to central or normal position, as shown in Fig. 5, but in doing so the stem K' does not affect the position of the closed slide valve L and the latter remains in a closed position, 30 it being understood that the collar K³ now abuts against the washer P under pressure of the spring N. Now, when the engineer releases the brakes and the engineer's valve I is moved into full release position, thus 35 allowing 30 pounds extra pressure to pass into the train pipe C and consequently into the left hand side of the cylinder A', then the piston K is forced to an extreme right hand position as shown in Fig. 6, whereby 40 the spring N is compressed, and the slide valve L is shifted back into an open position by the action of the collar K² against the left hand end of the slide valve L; thus, the triple valve exhaust pipe E is again connected 45 with the atmosphere, to allow ready escape of the air from the brake cylinder F with a view to release the brakes. Now the pressure in the train pipe C and the auxiliary reservoir H gradually equalizes, 50 and when this takes place like pressure is had on both faces of the piston K so that the spring N returns the piston K to a normal midway position without, however, shifting the slide valve L, and consequently 55 the same remains in an open position, as indicated in Fig. 3.

From the foregoing it will be seen that the slide valve L, normally open, is closed on setting the brakes, is unaffected on recharging the auxiliary reservoir H, and is moved to open position on releasing the brakes. In a like manner the piston K, normally in a midway position, is shifted to the extreme left on setting the brakes, is shifted back to 60 normal position on recharging the auxiliary 65

reservoir, and is shifted to the extreme right and compressing the spring N on releasing the breaks. It will also be noticed that the automatic retaining valve has nothing to do with the applying of the brakes and the engineer can apply the brakes on descending long grades and put the engineer's valve in running position and recharge the train without releasing the brakes or setting the brakes harder. Thus by the use of this device a 70 train of cars can be run down a steep grade 75 in perfect safety.

A three-way valve E² is preferably arranged in the pipe E to allow of cutting out the automatic retaining valve whenever it is desired to do so, it being understood that the exhaust from the triple valve then passes to the atmosphere by way of the said valve E².

It will be noticed that the automatic retaining valve does not allow the brakes to release until the engineer's valve has been moved to full release position and then the brakes release promptly.

By having the collars K² and K³ arranged relative to the slide valve L, as shown and described, the piston K is capable of moving about five-eighths of an inch either way without shifting the slide valve L, whereby a proper working of the automatic retaining valve is insured.

The piston K is provided with a peripheral packing ring to prevent leakage of pressure from one side of the piston or the other side, and thus allow the automatic retaining valve to work in full harmony with the triple valve.

The automatic retaining valve shown and described is very simple and durable in construction and capable of ready attachment to the fluid pressure brakes as now constructed.

Having thus described our invention, we 105 claim as new and desire to secure by Letters Patent:

1. An automatic retaining valve for fluid pressure brakes, comprising a casing having connection with the train pipe, triple valve exhaust and auxiliary reservoir, a valve in the casing and normally opening in triple valve exhaust to the atmosphere, and a piston in the casing and operating to move the valve into closed position on setting the 110 brakes, said piston being controlled by the pressure from the train pipe and the auxiliary reservoir and capable of moving without shifting the valve.

2. An automatic retaining valve for fluid pressure brakes, comprising a casing having connection with the train pipe, triple valve exhaust and the auxiliary reservoir, a valve in the casing and normally opening the triple valve exhaust to the atmosphere, and a piston in the casing and operating to move the valve into closed position on setting the 125 brakes and into open position on releasing the brakes, said piston being controlled by the pressure from the train pipe and auxiliary 130

reservoir and capable of moving without shifting the valve.

3. An automatic retaining valve for fluid pressure brakes, comprising a casing having connection with the train pipe, triple valve exhaust and the auxiliary reservoir, a valve in the casing and normally opening the triple valve exhaust to the atmosphere, a piston in the casing and connected with the valve to operate the same and to have movement independent of said valve, said piston being controlled by the pressure from the train pipe and the auxiliary reservoir and operating to move the valve into closed position on setting the brakes and into open position on releasing the brakes, and a tension device for returning the piston to normal position on equalizing of the pressure on opposite sides of the piston when releasing the brakes.
- 20 4. An automatic retaining valve for fluid pressure brakes, comprising a casing having connection with the train pipe, triple valve exhaust and auxiliary reservoir, a valve in the casing and normally opening the triple valve exhaust to the atmosphere, a piston in the casing and connected with the valve to operate the same and to have movement independent of the valve, said piston being controlled by the pressure from the train pipe and the auxiliary reservoir and operating to move the valve into closed position on setting the brakes and into open position on releasing the brakes, a tension device for returning the piston to normal position on equalizing of the pressure on opposite sides of the piston when releasing the brakes, and a three-way valve in the triple valve exhaust connection.

5. An automatic retaining valve for fluid pressure brakes, comprising a casing having connection with the train pipe, the triple valve exhaust and the auxiliary reservoir, a piston movable in the said casing and controlled by the pressures from the train pipe and the auxiliary reservoir, the said piston having a stem provided with spaced collars, a slide valve in the said casing and normally opening the triple valve exhaust to the atmosphere, the said valve being adapted to be engaged alternately by the said collars, to shift the valve into closed and open positions, and a tension device normally in inactive position and actuated by one of the said collars on shifting the piston when releasing the brakes.

6. An automatic retaining valve for fluid pressure brakes, comprising a casing having connection with the train pipe, the triple valve exhaust and the auxiliary reservoir, a piston movable in the said casing and controlled by the pressures from the train pipe and the auxiliary reservoir, the said piston having a stem provided with spaced collars, a slide valve in the said casing and normally

opening the triple valve exhaust to the atmosphere, the said valve being adapted to be engaged alternately by the said collars, to shift the valve into closed and open positions, and a tension device normally in inactive position and actuated by one of the said collars on shifting the piston when releasing the brakes, the said tension device returning the piston to normal position on the equalizing of the pressures on opposite sides of the piston.

7. An automatic retaining valve for fluid pressure brakes, comprising a casing having connection with the triple valve exhaust, the train pipe and the auxiliary reservoir, a piston movable in the said casing and under the influence of the pressures in the train pipe and the auxiliary reservoir, and a valve adapted to be shifted by the said piston, the piston being connected to the valve to move without shifting the valve, the said valve normally opening the triple valve exhaust to the atmosphere and being closed on setting the brakes, the valve being unaffected on recharging the auxiliary reservoir and being moved to open position on releasing the brakes.

8. An automatic retaining valve for fluid pressure brakes, comprising a casing having connection with the triple valve exhaust, the train pipe and the auxiliary reservoir, a piston movable in the said casing and under the influence of the pressures in the train pipe and the auxiliary reservoir, and a valve adapted to be shifted by the said piston, the said valve normally opening the triple valve exhaust to the atmosphere and being closed on setting the brakes, the valve being unaffected on recharging the auxiliary reservoir and being moved to open position on releasing the brakes, and the said piston being normally in an approximately midway position, and being shifted in one direction on setting the brakes, and returned to normal position on recharging the auxiliary reservoir, the said piston being shifted in the opposite direction on releasing the brakes.

9. An automatic retaining valve for fluid pressure brakes, comprising a casing having connection with the triple valve exhaust, the train pipe and the auxiliary reservoir, a piston movable in the said casing and under the influence of the pressures in the train pipe and the auxiliary reservoir, a valve adapted to be shifted by the said piston, the said valve normally opening the triple valve exhaust to the atmosphere and being closed on setting the brakes, the valve being unaffected on recharging the auxiliary reservoir and being moved to open position on releasing the brakes, and the said piston being normally in an approximately midway position and being shifted in one direction on setting the brakes, and returned to normal

position on recharging the auxiliary reservoir, the said piston being shifted in the opposite direction on releasing the brakes, and a tension device for the said piston and rendered 5 active on releasing the brakes and returning the piston to normal position on equalizing of the pressure on the opposite faces of the piston.
